UNITED STATES PATENT OFFICE

170,917

LAZY SUSAN OR SIMILAR ARTICLE

Robert L. Gruen, New York, N. Y., assignor to Continental Silver Co. Inc., a corporation of
New York

Application July 17, 1953, Serial No. 26,025

Term of patent 7 years

(Cl. D44—10)

To all whom it may concern:

Be it known that I, Robert L. Gruen, a citizen of the United States and residing at New York, in the county of New York and State of New York, have invented a new, original, and ornamental Design for a Lazy Susan or Similar Article, of which the following is a specification, reference being had to the accompanying drawing, forming part thereof, and in which:

Fig. 1 is a plan view of a Lazy Susan, showing my new design, and

Fig. 2 is a side elevation thereof.

I claim:

The ornamental design for a Lazy Susan or similar article, substantially as shown.

ROBERT L. GRUEN.
